UNITED STATES PATENT OFFICE.

LEMUEL M. BUSINELL AND SANFORD S. VAUGHAN, OF CHICAGO, ILLINOIS,
ASSIGNORS TO THE VAUGHAN & BUSINELL MANUFACTURING COMPANY,
OF SAME PLACE.

DESIGN FOR A WRENCH.

SPECIFICATION forming part of Design No. 29,109, dated July 26, 1898.

Application filed December 8, 1897. Serial No. 661,206. Term of patent 14 years.

To all whom it may concern:

Be it known that we, LEMUEL M. BUSINELL and SANFORD S. VAUGHAN, citizens of the United States, residing at Chicago, Cook county, Illinois, have invented and produced a new and original Design for Wrenches, of which the following is a specification.

In the accompanying drawings, Figure 1 is a side elevation of a wrench embodying my design, and Fig. 2 a cross-sectional view taken on line $x x$ of Fig. 1.

In the drawings, A is the handle portion; B, openings in the handle portion; D, jaws at one end of the handle portion, and C ribs at the inner edges of the jaws.

The leading feature of our design consists in a wrench provided with a handle portion

A, having openings B therein, the openings having their larger ends adjacent to each other and provided with a jaw portion D, 20 having a continuous rib C at the inner edges thereof, with depressed portions outside of the ribs, the whole presenting an ornate and attractive appearance, as shown in the drawings. 25

We claim—

The design for a wrench herein shown and described.

LEMUEL M. BUSINELL.
SANFORD S. VAUGHAN.
